UNITED STATES PATENT OFFICE.

EDWIN L. WHITE, OF BROOKLYN, NEW YORK, ASSIGNOR TO J. H. WHITE MANUFACTURING COMPANY, OF BROOKLYN, NEW YORK, A CORPORATION OF NEW YORK.

HANGER-LINK FOR SUSPENDING LIGHT-REFLECTING BOWLS.

1,233,828.

Specification of Letters Patent. Patented July 17, 1917.

Application filed December 8, 1916. Serial No. 135,784.

To all whom it may concern:

Be it known that I, EDWIN L. WHITE, a citizen of the United States, residing at the borough of Brooklyn, in the county of 5 Kings and State of New York, have invented an Improvement in Hanger-Links for Suspending Light-Reflecting Bowls, of which the following is a specification.

My invention relates to means for suspending bowls in lighting fixtures, and while applicable for connecting suspending chains to the common hooks or hangers usually employed upon bowls in lighting fixtures of the semi-indirect character, it is 10 especially designed for use in connection with a device invented by me for suspending bowls where used with a dome or shade where the use of chains is rendered unnecessary, which invention forms the subject 15 matter of a co-pending application for patent. My present invention consists essentially of a two part pivotally connected hook and link adapted to form a connection 20 between said suspending device and the hangers or projections on the light reflecting bowl.

The details of the invention are herein-after particularly described.

In the accompanying drawing:

Figure 1 is a side elevation of my improved link as closed.

Fig. 2 is a front elevation of the same.

Fig. 3 is a side elevation of the same open.

Fig. 4 is an elevation showing the device 35 connected to a hanger attached to a bowl suspended by chains, and

Fig. 5 is an elevation showing my invention as employed with a fixture in which a shade or dome is suspended over the bowl, 40 and suspending chains are dispensed with.

Similar reference characters denote like parts throughout the several views.

10, and 11, indicate two members pivotally connected together at their lower ends 45 by a pivot pin 12.

Each of these members are formed at their free ends with a hook 13, turned in the same direction.

That portion of the respective members 50 below these hook shaped ends is curved in opposite directions, overlapping each other at their extreme lower curved ends where joined by the pivot pin 12. The hooks 13 are of corresponding shape on each member 55 and overlap each other when the link is

closed. Upon the member 11, between the hook 13, and its body portion there is preferably an inwardly turned projection 14, which when the link is closed overlaps the upper part of the body portion of the member 10, and I also preferably provide a stop 15, upon the member 10, against which the projection 14, on the member 11, contacts when the link is closed, thereby assuring the overlapping of the hooked ends of the two 60 members in a uniform manner, with their edges in perfect alinement.

In Fig. 4, of the drawing, I have shown my improved device as forming a connection between an ordinary metal hanger 16, secured to the rim of a bowl 17, in a common manner, and the lower end of a suspending chain 18, but my invention is particularly adapted for use in connection with the suspending device forming the subject of my 70 aforesaid co-pending application, in which a shade or dome 19, is supported over a bowl 20, as illustrated in Fig. 5 of the drawing in the present application.

In such instance I employ a metal ring 21, 80 inserted within the customary central opening in the shade or dome with gripper fingers 22, to retain the ring in position, there being spaced arms 23, projecting from the ring and extending along the under surface 85 of the shade or dome, each arm being provided on its free end with an eye 24. The bowl 20 may be supplied with the ordinary hangers usually secured to the rim of such bowls as illustrated in Fig. 4, but my invention is particularly designed for use with 90 bowls formed with integral spaced headed lugs 25, as illustrated in Fig. 5.

In connecting such bowls by means of my present invention to my improved suspending device above named, the link is opened by swinging the members 10—11, apart on their pivotal connection 12, and the link placed around the lug 25, underneath its head, the members are then swung back 100 overlapping their respective hooks 13, and these hooks are then passed through the eyes 24 on the ends of the arms 23.

Three or more of these arms are employed together with the same number of headed 105 lugs 25, on the bowl 20. It will be seen that the bowl is thereby suspended centrally beneath the shade or dome 19, and there is no danger of the connecting links slipping off the lugs.

By the employment of my invention the bowls are suspended with great facility and in a secure and steady manner, without liability of injury.

5 I claim as my invention:

- 10 1. A hanger link for suspending bowls in lighting fixtures, comprising two flat members curved in opposite directions with their lower ends overlapped and pivotally connected, each provided at its upper end with a flat hook of like shape and turned in the same direction, which hooks when the members are swung together overlap and match each other in contact.
- 15 2. A hanger link for suspending bowls in lighting fixtures, comprising two flat members curved in opposite directions with their lower ends overlapped and pivotally connected, each provided at its upper end with a flat hook of like shape and turned in the same direction, which hooks when the members are swung together overlap and match each other in contact, a stop upon one of said members, and a flat inwardly turned projection at the base of the hook upon the other member for contact with the said stop.

3. In a lighting fixture, and in combination, a shade or dome, means for supporting the same upon the fixture, a light reflecting bowl provided with spaced headed lugs adjacent its upper edge, a suspending device connected to said shade or dome and provided with spaced projecting arms extending along the under surface of said shade or dome and each provided at its free end with an eye, and a link composed of two flat metallic members overlapped at their lower ends and pivotally connected at such point, each member being provided at its upper end with an integral hook of corresponding shape and turned in the same direction, the body portion of the respective members being curved in opposite direction and surrounding the said lugs upon the bowl under their heads, and the said hooks in an overlapped position being passed through the eyes on the ends of said projecting arms, whereby said bowl is suspended beneath said shade or dome.

Signed by me this 4th day of December, 1916.

EDWIN L. WHITE.
